UNITED STATES PATENT OFFICE.

LENNA BERGESON, OF LOS ANGELES, CALIFORNIA.

DESIGN FOR A DOLL.

Application filed November 16, 1923. Serial No. 7,773. Term of patent 3½ years.

To all whom it may concern:

Be it known that I, LENNA BERGESON, a citizen of the United States, residing at Los Angeles, in the county of Los Angeles, State of California, have invented a new, original, and ornamental Design for a Doll, of which the following is a specification, reference being had to the accompanying drawings, forming part thereof.

Fig. 1 is a front elevation of the doll.
Fig. 2 is a side elevation of the doll.
Fig. 3 is a back elevation of the doll.
Fig. 4 is a perspective.

I claim:

The ornamental design for a doll, as shown.

LENNA BERGESON.
